UNITED STATES PATENT OFFICE

117,870

DESIGN FOR A HAT

Lauretta Millar, Maplewood, N. J.

Application July 20, 1939, Serial No. 86,094

Term of patent 3½ years

To all whom it may concern:

Be it known that I, Lauretta Millar, a citizen of the United States, residing at Maplewood, in the county of Essex and State of New Jersey, have invented a new, original, and ornamental Design for Hats, of which the following is a specification, reference being had to the accompanying drawing, forming a part thereof.

Fig. 1 is a front view of a hat showing my new design;

Fig. 2 is a rear view of the hat shown in Fig. 1; and

Fig. 3 is a perspective view of the hat in the shape it assumes when worn.

I claim:

The ornamental design for a hat, as shown.

LAURETTA MILLAR.
